UNITED STATES PATENT OFFICE.

CHRISTOPHER T. BARRON, OF LAWRENCE, MASSACHUSETTS.

PUSHING ATTACHMENT FOR RAILWAY TRAIN UNITS.

1,320,359.

Specification of Letters Patent. Patented Oct. 28, 1919.

Application filed August 30, 1919. Serial No. 320,928.

To all whom it may concern:

Be it known that I, CHRISTOPHER T. BARRON, a citizen of the United States, residing at Lawrence, in the county of Essex and 5 State of Massachusetts, have invented new and useful Improvements in Pushing Attachments for Railway Train Units, of which the following is a specification:

This invention relates to means whereby a 10 pushing train unit such as that constituted by a locomotive engine and its tender, running on one track, may be caused to push another train unit such as a freight car, on another track. 15 Each unit is customarily provided at a corner portion with a cupped socket, the socket of each unit being adapted to detachably engage an elongated stiff pole, or, as it is usually called, a stake, adapted to extend 20 diagonally from the unit on one track to the unit on the other track, the arrangement being such that when the pushing unit is moved by its own power, it pushes the other unit through the stake. When the movement 25 of the pushing unit is checked, the pushed unit is moved onward by its own momentum and leaves the stake.

It is now the common practice to employ a stake which has no direct connection with 30 either unit, and falls to the ground, sometimes with disastrous results, when the movement of the pushing unit is checked. It is necessary for a brakeman, or other attendant, to support the stake by his hands, in 35 position to engage the sockets of the two units, when one approaches the other, the operation being fraught with danger to the attendant.

It has been proposed heretofore to provide 40 means for so connecting the stake with the pushing unit as to eliminate the objections above mentioned, but such means have been more or less complicated, expensive and inconvenient, and have not been organized to 45 permit the stake to be quickly installed for use and removed for storage when its use is no longer required.

My invention has for its object to provide 50 improved means for detachably connecting a pushing stake with the socket of a pushing train unit, in such manner that the weight of the stake is a factor in holding its inner end in separable engagement with the socket, and the stake is supported in a substantially 55 horizontal position and free to be swung horizontally by an attendant.

The invention is embodied in the improvements which I will now proceed to describe and claim.

Of the accompanying drawings forming a 60 part of this specification,—

Figure 1 is a perspective view of a portion of a locomotive tender, equipped with an attachment embodying my invention, and a portion of a freight car with which the stake 65 is engaged.

Fig. 2 is a side view of the stake.

Fig. 3 is a plan view showing portions of 70 two tracks, two train units and a stake between the units.

The same reference characters indicate the same parts in all of the figures.

In the drawings, *a* represents a portion of a pushing unit of a railroad train, the unit being in this case a locomotive tender, provided at its rear end with the usual corner socket *b*, adapted to be engaged by the inner end of a pushing stake *c*, the outer end of which is adapted to engage a similar corner socket *b'*, on a freight car *d*, the unit *a* being 80 on one track, and the unit *d* on another track. The stake *c* is usually a wooden pole, about eight feet in length.

In carrying out my invention I provide 85 the unit *a* with a longer suspending cable 12, and a shorter suspending cable 13, these cables being preferably composed of chain links. The shorter cable is connected with the unit *a* at a point 14 which is relatively 90 near and above the socket *b*. The longer cable 12 is connected with the unit *a* at a higher point 15.

I also provide the stake *c* with two eyes 16 and 17, the eye 17 being at the inner end portion of the stake, and the eye 16 at about 95 the mid length of the stake. Said eyes are adapted to be detachably engaged with hooks 18 on the lower ends of the cables 12 and 13.

The arrangement is such that when the 100 stake eyes are engaged with the cables, the weight of the stake is a factor in holding its inner end in separable engagement with the socket *b*, the stake being supported in a substantially horizontal position, and free to be 105 swung horizontally on a center of oscillation formed by the socket *b*.

The stake is usually stored when not in use, on suitable supports not shown, under the unit *a*. When the use of the stake is required, the attendant removes it from said supports, couples the cables 12 and 13 to the 110

eyes 16 and 17, and inserts the inner end of the stake in the socket *b*. The stake is now supported entirely by the unit *a*, so that the operator standing between two tracks is enabled to readily cause the outer end of the stake to engage the socket *b'* on the unit to be pushed. When the movement of the pushing unit *a* is checked, and the pushed unit *d* leaves the stake, the latter remains supported by the pushing unit until removed by the attendant. In removing the stake the attendant detaches the cables from the stake eyes, and then stores the stake as usual.

The cables 12 and 13 are preferably permanently connected at their upper ends with the unit *a*, so that when not in use, they hang vertically out of the way, as indicated at the left in Fig. 1.

The eye 17 is preferably formed in a socketed metal cap 20, which forms the inner end of the stake. The eye 16 may be formed on a bolt passed through the thickened mid-length portion of the stake.

The pushing unit *a* is usually provided with two sockets *b*, and with two pairs of cables 12 and 13, as shown by Fig. 1, the unit *d* being provided with a corresponding number of sockets *b'*. In practice, the unit *d*, if a freight car, is provided with four sockets, one at each corner. It is obvious that the sockets *b* on the pushing unit, and the cables 12 and 13, may be attached to the forward portion of that part of the pushing unit constituted by the locomotive proper, the term "pushing unit" as used herein, being intended to include either the locomotive or its tender, or both.

It is obvious that the cables 12 and 13 may be permanently connected with the stake, and detachably connected with the pushing unit. Said cables constitute an embodiment of stake-supporting means adapted for connection with the stake and with the pushing unit, and arranged, when so connected, to hold one end of the stake in separable engagement with the socket *b*, and to permit outward endwise movement of the stake to separate its inner end from the socket. Said means may be otherwise embodied to perform the function stated, without departing from the spirit of the invention.

The eye 16 should be so arranged that the stake, if free to swing in a vertical plane on the center formed by said eye, would

swing downward at its inner end. In other words the inner portion of the stake between the eye 16 and the inner end is somewhat heavier than the outer portion between said eye and the outer end. This arrangement enables the shorter cable 13 to prevent the stake from being swung by gravity in a vertical plane on the center formed by the eye 16, so that in the event of accidental separation of the inner end of the stake from the socket *b*, the outer end cannot swing downward.

I claim:

1. In combination with a pushing-train-unit having a stake-engaging socket, longer and shorter suspending cables, each connected at one end with said unit at a point above the socket, the shorter cable being connected at a point relatively near and above the socket, and the longer cable at a higher point, and a stake formed at its inner end to engage the said socket, and at its outer end to engage a socket in a train unit to be pushed, said stake being provided at its inner end portion with means for engaging the shorter cable, and at a point between its ends with means for engaging the longer cable, said cables being adapted to hold the inner end of the stake in swinging engagement with the propelling-unit-socket, and to coöperate with said socket in supporting the stake in a substantially horizontal position, the weight of the stake being a factor in holding the inner end of the stake in separable engagement with the pushing unit socket.

2. A pushing attachment for railway train units, comprising a pushing stake formed at its inner end to separably engage a socket on a pushing-train-unit, and at its outer end to separably engage a socket on a train-unit to be pushed, and provided at its inner end portion with an inner cable-engaging eye, and with an outer cable-engaging eye at substantially the mid-length of the stake, a longer suspending cable engageable with the outer eye and with a train unit, and a shorter suspending cable engageable with the inner eye and with said unit, the portion of the stake between the outer eye and the inner end being heavier than the portion between the outer eye and the outer end.

In testimony whereof I have affixed my signature.

CHRISTOPHER T. BARRON.
